UNITED STATES PATENT OFFICE.

JOHN HARRIS, OF CLEVELAND, OHIO.

ACETYLENE-GENERATOR.

1,237,898.

Specification of Letters Patent. Patented Aug. 21, 1917.

Application filed October 12, 1914. Serial No. 366,194.

To all whom it may concern:

Be it known that I, JOHN HARRIS, a citizen of the United States, residing at Cleveland, in the county of Cuyahoga and State of Ohio, have invented a certain new and useful Improvement in Acetylene-Generators, of which the following is a full, clear, and exact description, reference being had to the accompanying drawings.

This invention relates to apparatus for generating acetylene-gas of high pressure, such as is used with blow pipes for so-called "autogenous welding"; and has for its principal object to provide an apparatus of this character that is thoroughly safe and reliable, the same being provided with means whereby it is vented when the pressure therein becomes excessive, or when the generator is opened for the purpose of draining it, or for supplying it with water or carbid; the aforesaid means being automatically operated by internal pressure, when the same becomes excessive, and also mechanically actuated prior to the opening of the generator for any of the aforesaid purposes. By thus being mechanically operated every time the generator is opened, which occurs quite frequently, the venting means is kept in perfect working condition, and avoids the possibility of its refusing to operate by becoming stuck through inactivity, which is liable to be the case in safety devices that depend for their operation, exclusively, upon the rise of pressure within the generator, beyond a safe condition.

A diaphragm is employed in carrying out the above objects, and in the event that the diaphragm becomes fractured, it is a further object of my invention to provide an arrangement whereby the gas thus liberated from the generator will be carried off through a suitable vent pipe.

Generally speaking my invention may be defined as consisting of the combinations of elements set forth in the annexed claims and illustrated in the accompanying drawings forming part hereof, wherein Figure 1 is a front elevation of the apparatus; Figs. 2 and 3 are central vertical sections of the vent valve, the planes of the respective sections being substantially at right angles to each other; and Fig. 4 is an enlarged sectional detail of parts of the vent valve.

Taking up a detailed description of the invention by the use of reference characters,

1 represents the generating chamber of the apparatus above which is supported, upon a neck 2, a carbid hopper 3.

Following the usual construction of apparatus of this character, the generating chamber is provided with a filling pipe through which it may be supplied with water, and in the present instance the filling pipe is equipped with a valve 19 having an operating handle 18 that is secured to the stem 21 of the valve. The upper portion of the handle is of segmental formation, as shown at 20, and the arc of the segmental portion is concentric with the valve stem 21. When the handle 18 is in the position shown in full lines, the valve 19 is closed; but when the handle is swung upward through substantially 45°, or into the position shown in dotted lines, the valve is opened.

It is essential that the apparatus be exhausted, prior to the opening of the valve 19, and mechanism for preventing the operation of this valve until the apparatus has been exhausted, will now be described.

A vent valve shown in detail in Figs. 2, 3, and 4, comprises upper and lower casing members 35 and 36, the adjacent edges of which are each provided with a horizontal flange 37 and 38, respectively. Between these flanges is securely clamped the periphery of a flexible diaphragm 39. The casing member 35 converges toward its upper end and terminates in a cylindrical neck 40 which has applied to it a cap 41, and threaded within the neck, and adapted to be covered by the cap 41, is a spring casing 42, against the top wall of which bears the upper end of a coil spring 43. The lower end of this spring surrounds a shank 44 of a yoke 45 that is formed integral with a disk 46, from the underneath side of which depends a central stud 47. By means of the stud 47, and the nut 48 applied thereto, there is clamped to the disk 46, plate 49, diaphragm 39, and a valve member 50, having an annular pliable contact portion 51, preferably of rubber. The contact portion of the valve member is arranged to engage a seat 52 of corresponding shape, which is located centrally within the lower casing member 36, and is preferably formed by the upper end of an internal tubular extension which projects from one side of the casing, and with which extension is connected the vent pipe 53.

The valve member 50 may be caused to

bear upon its seat 52, at any desired pressure, such pressure being obtained by varying the tension of the spring 43 which is accomplished through the adjustment of the 5 casing 42, that is threaded into the upper end of the neck 40, said casing 42 being provided with a portion 55 for the application of a wrench or other tool. The lower end of the casing member 36 terminates in an 10 internally threaded boss 56 that has connection, through the pipe 57, with the generating chamber 1. Now, therefore, when the pressure within the generating chamber exceeds that of the tension of the spring 43 15 the diaphragm 39 will be elevated to remove the valve member 50 from its seat and allow a quantity of gas to escape through the vent pipe 53.

Extending through the yoke 45 is an eccentric 60 upon the shaft 61, journaled in the opposed walls of the upper casing member 35, the same being provided with a suitable packing gland 62 where it passes through the wall of said casing member. 20 Applied to the end of the shaft 61, beyond the packing gland 62, is an arm 63 which has its free end connected, by the link 64, to a lever 65 that is journaled at 66 to a lug 67 projecting from the front of the generating 25 chamber 1. This lever carries a segment 68, the curved face of which is concentric with the pivot 66, and which has a radius equal to the distance between said pivot and the forward end of the handle 18 when the 30 latter is in its lower position; the lug 67 being so located with respect to said handle as to cause the segment of the lever 65, and the segmental portion of the said handle to be in substantially the same plane. It may 35 be stated, also, that the radius of the segmental portion of the valve handle is such as will cause its periphery to just escape one end of the segment 68 when the lever 65 is vertical. Therefore, the handle 18 can be 40 operated only when the lever 65 is in its extreme upper position, and the lever 65 can be operated only when the handle 18 is in its extreme lower position. It is obvious 45 from this that the valve 19 cannot be opened 50 for the purpose of supplying water to the generating chamber until the lever 65 has been elevated to operate the valve 50 and vent the apparatus.

If, through any cause, the pressure within 55 the apparatus becomes excessive and produces a condition which may be considered dangerous, the diaphragm 39 will be elevated to remove the valve 50 from its seat 52 and allow the excess gas to escape through 60 the vent pipe 53, which leads to the exterior of the building. As previously pointed out, the vent valve may be regulated to resist varying degrees of pressure through the adjustment of the spring 43, in actual practice, the spring being adjusted to fifteen pounds

pressure, as required by insurance companies.

It is clear from what has been described, that the valve 50 is compelled to be removed from its seat prior to each operation 70 of the filling valve 19, whereby the former valve is kept in perfect working condition and is prevented from sticking or corroding, by such frequent mechanical operations.

In case the diaphragm 39 becomes fractured, the gas which would thus escape into the upper portion of the casing would be led off through a branch pipe 130, which joins the main vent pipe 53 at 131. The branch pipe has communication with the interior 80 of the casing member 35 of the vent valve, through a nipple 132.

Having thus described my invention, what I claim is:

1. The combination with apparatus of the 85 character set forth, of a valve comprising a casing that is composed of two members, a diaphragm that is clamped between the adjacent edges thereof, one of said members having an internal hollow outlet extension 90 that terminates in a valve seat which occupies a plane substantially parallel to that of the diaphragm, an abutment attached to and spaced from the opposite side of the diaphragm, a cam for coöperation with said 95 abutment, a shaft upon which said cam is mounted and which projects through and is journaled within the wall of the valve casing, means applied to said shaft whereby the same may be oscillated, and a spring for 100 moving the diaphragm toward the valve seat.

2. The combination with apparatus of the character set forth, of a valve comprising a hollow casing that is composed of two members the adjacent ends of which are attached 105 together, a diaphragm, the periphery of which is clamped between said members, one of said members having an internal hollow outlet extension which terminates at its inner end in a valve seat, a valve member for 110 coöperation therewith that is carried by the diaphragm, a yoke that is applied to the opposite side of the diaphragm, a spring for moving the diaphragm toward the valve seat, an eccentric within the yoke and arranged to engage the wall thereof that is opposite the diaphragm, a shaft connected to said eccentric and extending through the side of the valve casing, and means applied thereto whereby said eccentric may be rocked 115 to move the diaphragm in a direction away from the valve seat.

3. The combination with apparatus of the character set forth, of a valve comprising a hollow casing that is composed of two members the adjacent ends of which are attached 125 together, a diaphragm, the periphery of which is clamped between said members, one of said members having an internal hollow outlet extension which terminates at its 130

inner end in a valve seat, a valve member for coöperation therewith that is carried by the diaphragm, a yoke that is applied to the opposite side of the diaphragm and having a shank, a spring casing adjustably connected to the end of the valve casing, a spring interposed between the end of said spring casing and the aforesaid yoke and surrounding the shank thereof, an eccentric within 10 the yoke and arranged to engage the wall thereof that is opposite the diaphragm, a shaft connected to said eccentric and extending through the side of the valve casing, and means applied thereto whereby said eccentric 15 may be rocked to move the diaphragm in a direction away from the valve seat.

4. In apparatus of the character set forth, the combination of a hollow hermetically sealed casing that is composed of two members having their adjacent ends connected together, a diaphragm having its periphery clamped between said members, thus dividing the casing into separate compartments, a vent pipe leading from each compartment, 20 communicative connections between the apparatus and one of said compartments, a valve for controlling the flow through the vent pipe of the last mentioned compartment, and operative connections between the 25 diaphragm and said valve.

5. In a device of the character set forth, the combination of a casing member having an inlet, an open side, and a tubular outlet 30 extension which terminates in a valve seat that is in a plane substantially parallel to

the plane of said open side, a diaphragm closing the open side of the casing, a plate applied to the side of the diaphragm opposite the valve seat, a second plate applied to the opposite side of the diaphragm, a pad 40 of compressible material, a binder attached to the edge of the second plate between which and said edge the periphery of the pad is confined, a washer applied to the central part of the pad whereby only a portion of the pad is exposed for coöperation with the valve seat, and means passing through and binding together the first plate, the diaphragm, the second plate, the pad, and the washer. 45

6. In apparatus of the character set forth, the combination of a hermetically sealed diaphragm casing, an imperforate diaphragm dividing the casing into two compartments to the end that communication between the compartments is prevented except upon a rupture of the diaphragm, and means having connection with said diaphragm so as to be operated thereby, one of said compartments having communicative connection with the interior of the apparatus and the other having communication with a vent conduit. 55

In testimony whereof, I hereunto affix my signature in the presence of two witnesses. 60 65

JOHN HARRIS.
